UNITED STATES PATENT OFFICE

JAMES T. COWLEY, OF SYRACUSE, NEW YORK, ASSIGNOR TO THE LAMSON COMPANY,
OF SYRACUSE, NEW YORK, A CORPORATION OF MASSACHUSETTS

POWER CONTROLLER

Application filed November 7, 1928. Serial No. 317,857.

This invention pertains to power controllers for pneumatic despatch systems and relates more particularly to automatically actuated controllers of the so-called minimum flow type of which my Patent No. 1,536,424 dated May 5, 1925 furnishes an example.

Pneumatic despatch tube apparatus of the minimum flow type are vacuum systems as distinguished from pressure systems and are open or continuous current systems as distinguished from closed systems in which normally no air current is maintained through the line when the line is idle. Controllers for such open or continuous current vacuum systems of the minimum flow type comprise essentially an air-controlling valve, located in the exhaust pipe between the transit tube and the air exhauster or vacuum drum, which normally cuts down the air current to a minimum when the line is idle, never wholly cutting it off but at all times permitting a continuous flow of relatively small volume called "minimum flow", and a pneumatic, such as a piston or diaphragm, which responds to a change of pressure in the line due to the momentary cutting off or checking of the minimum flow of air by the insertion of a carrier into the tube and by its response opens wide the controlling valve to permit a full flow of air for driving the carrier. As is common in describing devices of this type I herein employ the term "pneumatic" to designate broadly any pressure or vacuum actuated instrumentality, for example, a flexible diaphragm, piston, or bellows, by means of which fluid pressure is converted into mechanical motion.

As above stated, the pneumatic is arranged to respond to the slight variation in pressure in the tube due to the reduction or cutting off of the minimum flow by the insertion of the carrier, and to insure certainty of operation, the pneumatic must respond sensitively to very slight pressure changes. In order that the main valve may close at the proper time it is usual to provide some auxiliary-controlling means, operative either after a predetermined time interval, or in response to the discharge of a carrier from the tube, for bringing about a change in pressure condi-

tions at the pneumatic, thereby causing the latter to restore the main controlling valve to closed position. When the main valve closes, the column of air which has been flowing in the line is blocked, and a series of compression waves with alternating troughs of low pressure is set up in the tube. Sometimes the resulting pressure condition is such as to simulate that produced by cutting off the minimum flow, and the diaphragm or other pneumatic immediately responds and again opens the main valve, although no carrier may be in the line at the time. If, to avoid this difficulty, the pneumatic be made less sensitive, it may then fail to respond to the introduction of a carrier in the line and thus, under some conditions, great difficulty is experienced in setting the control apparatus so that it may be depended upon for a long period of use.

In order to avoid the above difficulties resort has been had in some instances to very complicated structures involving the use of several interacting pneumatics, and requiring the greatest care in initial adjustment and in maintenance. Such devices are expensive to build and install and in many instances the adjustable elements are so disposed that it is extremely difficult to obtain access to them in the limited space available where the controller is installed.

Quite commonly the pneumatic moves rather slowly in its return to normal position, and sometimes decreases in speed as it approaches normal position, and as the main valve is usually connected directly to this diaphragm, the main valve closes slowly, thus gradually cutting off the air current in the line so that in some cases the carrier is left stranded at some point within the line.

In accordance with the present invention I provide control apparatus in which the main controlling valve remains fully open until the pneumatic has nearly completed its return movement, and then closes very suddenly so that there is no tapering off or wire drawing of the air current in the tube. I also provide for shielding the pneumatic from variations in pressure conditions in the tube subsequent to the closure of the main control-

ling valve until conditions have returned substantially to normal, that is to say, to normal minimum flow conditions. In conjunction with and in addition to the above desirable features I provide others, including an arrangement which insures adequate force for returning the pneumatic to its normal position, a simplified and cheaper construction of parts, and the disposal of the adjusting elements so that they are all readily accessible from the front side of the apparatus.

In the accompanying drawings in which I have illustrated one desirable embodiment of the invention, by way of example:

15 Fig. 1 is a fragmentary elevation illustrating part of the central station desk of a pneumatic despatch system having my improved power control apparatus applied thereto;

20 Fig. 2 is a fragmentary vertical section to larger scale, showing details of the power control apparatus with its parts in normal position; that is to say, with the controlling valve closed;

25 Fig. 3 is a view similar to Fig. 2, but showing the controlling valve wide open, the auxiliary valve open, and the pilot valve unseated;

30 Fig. 4 is a view similar to Fig. 3, showing the controlling and pilot valves open, but with the auxiliary valve closed; and

35 Fig. 5 is a view similar to Fig. 4, but showing the pneumatic which actuates the main valve restored to its normal position, the auxiliary valve closed, the main valve on the point of closing, and the pilot valve closed.

Referring to Fig. 1, the numeral 1 indicates a fragmentary portion of the central station desk of a pneumatic despatch system. This system may comprise, for example, a tube 3 leading to an outlying or sending station from which another run 4 of the tube returns to the central station. The tube 3 is provided with a despatch terminal 2 and the tube 4 with a delivery terminal 5, the tubes 3 and 4 collectively constituting a single transmission line of the system. The tube 4 is provided with a continuation 6 connecting it to an individual power controlling device indicated generally at 7. This power controlling device is connected by a suction tube 8 to a vacuum drum or header 9 in which a low pressure is continuously maintained by means of a suitable pump or exhauster not shown. The above arrangement in general is old and well known and requires no further specific description, the present invention being confined to improvements in the power control apparatus per se.

Referring to Figs. 2 and 3, the improved power control apparatus comprises a casing 10, preferably of more or less cylindrical form, having the upper and lower parts 11 and 12 adapted to receive the lower end of the tube 6 and the upper end of the tube 8, respectively. The casing 10 is provided with

an elongate axial passage 13 which is aligned with the tubes 6 and 8, thus forming an intermediate portion of the air conduit.

A shaft 14 extends transversely across the passage 13, being journaled in suitable bearings in the walls of the casing 10. This shaft carries a controlling or main valve 15, preferably of butterfly type, which in closed position, is preferably inclined to the axis of the conduit as shown in Fig. 2. Preferably the upper wing of this valve is of slightly greater area than the lower wing so that the air pressure tends to hold the valve closed.

Preferably one end of the shaft 14 projects beyond the outer surface of the casing and is provided with an arm 16 adapted to engage a stop pin 17 (Fig. 1) when the valve is in its full open position. When in the latter position the valve is preferably inclined slightly to the axis of the passage 13 as shown in Fig. 3, so that the pressure of the air against the upper surface of the valve is sufficient to hold it open.

At one side of the casing I provide a housing consisting of the parts 18 and 19 between which the edge portion of a diaphragm 20 is clamped. The diaphragm 20 divides the space within the housing into chambers 21 and 22, the latter being open to the outer atmosphere through a port 23 in the part 19. The chamber 21 normally communicates with the passage 13 by means of a port 24. A leak passage 25 extends inwardly through the member 18 into the chamber 21, and this passage is adjustable in size by means of a screw 26.

When the valve 15 is closed, as indicated in Fig. 2, a small but continuous flow of air commonly known as the minimum flow is permitted to by-pass about the valve 15 through a port 27. The size of this port may be adjusted by means of a screw 28 having a knurled head 29 engaged by a spring detent 30 secured to the part 18. This screw 28 may be turned by means of a screw driver in the ordinary way or by hand to adjust the size of the port 27, but when once adjusted it retains an adjusted position by the engagement of the spring detent 30 with the head 29.

115 A rod or stem member 31 is clamped to the center of the main diaphragm 20 in any suitable and usual way and is guided to slide in aligned apertures in the walls of the casing 10 and in the part 19. The upper right-hand end of this stem 31, as viewed in Fig. 2, is provided with a stop collar or flange 32 which engages the forked end 33 of a lever 34 mounted to turn upon a pin 35 carried by a bracket 36 projecting from the member 19. The lever 34 has a short, angularly disposed arm 37 to which one end of a tension spring 38 is connected. The other end of the spring 38 is secured to an adjusting member 39 mounted in a bracket 40 projecting from the

part 19. The angularity of the arms 34 and 37 of the actuating lever is such that when the diaphragm occupies the position shown in Fig. 2 the spring exerts a maximum pressure, it being noted by reference to Fig. 4 that when the diaphragm is moved away from its normal position the arm 37 approaches alignment with a line passing through the pivot 35 and the adjusting screw 39 so that the effective leverage through which the spring acts is less than when the parts are arranged as shown in Fig. 2.

The lower wing 15^a of the valve 15 is provided with an opening 41 through which the stem 31 passes loosely. Preferably that portion 42 of the stem 31 which passes through the opening 41 is made as a separate element of smaller diameter than the main portion of the stem 31 and fits within an axial socket in the latter, being secured therein in any desired manner. With this construction a shoulder is formed at the point 43, such shoulder constituting an actuating abutment engageable with the valve 15 to push the latter open as the stem 31 moves to the left as viewed in Fig. 2. At the opposite side of the wing 15^a, the stem member 42 carries a second abutment 44, the abutments 43 and 44 being spaced apart to provide lost motion in the actuation of the valve as hereinafter more fully described. Preferably the abutment 44 is adjustable on the part 42.

An auxiliary valve 45 controls the port 24. This valve is mounted upon a sliding valve stem 46 which extends transversely across the passage 13 and into the housing of an auxiliary pneumatic. This housing preferably comprises the parts 47 and 48 having the edges of the auxiliary diaphragm 49 clamped between them. This diaphragm divides the space within the auxiliary housing into two chambers 50 and 51, respectively, the latter always communicating with the outside atmosphere by means of a port 52. The diaphragm 49 is clamped to a sleeve 53 which slides freely on an extension 54 of the stem 46. Preferably extension 54 is of smaller diameter than the main part of the stem 46 thus providing an abutment shoulder at the point 55. This abutment shoulder is engaged by the sleeve 53 when the diaphragm 49 occupies the position shown in Fig. 2, thus holding the auxiliary valve 45 off of its seat. The stem portion 54 carries a second abutment 55^a normally spaced from the sleeve 53 and constituting a stop to limit movement of the diaphragm 49 to the left as viewed in Fig. 2. Preferably the abutment 55^a is adjustable along the part 54. A coiled spring 56 within the chamber 50 constantly tends to move the diaphragm 49 to the left as viewed in Fig. 2.

The chamber 50 communicates by means of a leak passage 57 with a chamber 58 concentric with the stem member 42 of the main

diaphragm, and this chamber 58 in turn communicates by means of a passage 59 with the passage 13 in the casing 10 at a point below the valve 15. An adjusting screw 60 provides for varying the effective diameter of the leak passage 57.

The outer end of the chamber 58 is defined by an annular valve seat 61 against which a valve 62 is normally pressed by atmospheric pressure.

The stem member 42 preferably terminates in a screw-threaded portion 64 of reduced diameter, such portion passing loosely through the valve 62. At the junction of the part 64 with the part 42 an abutment shoulder 63 is formed and when in the movement of the stem 42 to the left, as viewed in Fig. 2, this abutment engages the valve 62, it unseats the latter, thus equalizing the air pressure upon its opposite side. A spring 65 housed in the chamber 58 tends to unseat the valve 62, and when the valve has been unseated by the action of the abutment shoulder 63, the spring 65 holds this valve unseated until it is positively restored by engagement with an abutment 66 adjustably mounted upon the screw-threaded portion 64 of the stem. The parts 55^a and 66 are adjusted in the factory and preferably pinned in adjusted position and are not further adjusted during use.

Normally the several parts of the power controller occupy the position shown in Fig. 2, the main controlling valve 15 being closed and in the inclined position shown; the diaphragm 20 being held in its extreme right-hand position by the action of the spring 38 and the lever 34; the abutments 43 and 44 being spaced from the valve 15 at opposite sides thereof; the auxiliary valve 45 being open; the pilot valve 62 being closed; and the diaphragm 49 being held in its right-hand position against the tension of spring 56 by atmospheric pressure acting upon its left-hand seat. The chamber 50 is in communication with the suction tube 8 through the passages 57 and 59, and a minimum flow of air is taking place, such flow passing from the tube 6 through the by-pass 27 and into the suction tube 8.

When a carrier is introduced into the transmission tube the minimum flow is substantially cut off so that the pressure drops in the passage 13. As this passage communicates by means of the port 24 with the chamber 21, the pressure in the latter chamber also drops and atmospheric pressure, acting on the outer side of the diaphragm 20, moves the latter to the left as shown in Fig. 3. During the latter part of this movement the abutment 43 engages the valve 15 and swings the latter to a position just beyond the vertical, whereupon the air current acting upon the valve begins to exert pressure tending to continue the movement of the valve in a clockwise di-

rection, such movement being stopped by engagement of the finger 16 with the pin 17. Thus, in its fully open position, the valve wing 15^a may be slightly spaced from the abutment 43 which avoids the necessity of exact adjustment of the parts. As the valve 15 approaches its fully open position, the abutment 63 engages the pilot valve 62 and unseats the latter, whereupon the spring 65 moves the pilot valve down against the abutment 66 as shown in Fig. 3.

The opening of the pilot valve 62 breaks the vacuum in the chamber 50 and permits the spring 56 to push the diaphragm 49 to the left as viewed in Fig. 2 until it occupies the position shown in Fig. 4. Near the end of this movement of the auxiliary diaphragm 49 the sleeve 53 strikes the abutment 55 and thus moves the stem 46 and closes the valve 45, cutting off communication between the chamber 21 and passage 13.

The parts now remain substantially in this position until through leakage at the port 25, sufficient pressure is built up in the chamber 21 to permit the spring 38 to move the diaphragm 20 with the stem 31 to the right. During the early part of this movement of the stem 31 the valve 15 remains fully open but when the abutment 44 engages the valve 40 it swings the latter to the left or in a counter-clockwise direction until the valve is slightly inclined to the left of the vertical whereupon it is seized by the air current and suddenly closed, the spacing of the abutments 43 and 44 permitting this relative motion between the parts. This sudden closure of the controlling valve cuts off the current quickly, although leaving a full flow up to the moment of cut-off.

As the diaphragm 20 approaches its normal right-hand position the abutment 66 returns the pilot valve 62 to its seat. The suction in the pipe 8 now acts, through the passages 59, 58 and 57, to reduce the pressure in the chamber 50, but by setting the adjusting screw 60 so as to restrict the passage 57 to the proper amount, a considerable time interval may elapse before the suction in the chamber 50 is sufficient to overcome the spring 56 and thus open the valve 45. The spacing of the abutments 55 and 55^a also results in delay in opening the valve 45. Thus the valve 45 remains closed for an appreciable time after the closure of the valve 15 and, although the closing of the valve 15 may result in setting up a series of powerful compression waves in the transmission line, these waves are not transmitted to the chamber 21 so as to affect the diaphragm 20, and it is only after the subsidence of this series of pressure waves that the valve 45 opens. It is thus possible to adjust the diaphragm 20 so as to respond very sensitively to pressure changes in the transmission line without

danger that it will respond improperly upon closure of the main valve.

It may be noted that the diaphragm housing comprising the parts 18 and 19 is so disposed that the stem 31 of the diaphragm 30 is oblique to the axis of the passage 13. The purpose of this arrangement is two-fold; first, it permits such an inclination of the stem 31 that the latter makes substantially equal angles with the valve 15 when the latter is closed and when it is open, respectively, thus securing equal movement of the valve by the diaphragm stem in both directions of movement of the latter. Second, the arrangement of the diaphragm housing as disclosed provides ample space for the adjusting screws 26, 29 and 39 so that they are accessible from the front side of the power control device. Thus, when the device is installed in the cramped quarters usually provided for such apparatus, it is possible to get at all of these adjustable parts without difficulty.

It has already been pointed out that the spring 38 and the lever 34 are preferably so arranged that the force for returning the diaphragm 20 to its normal position is slightly greater as it approaches the end of its movement toward normal position than at the beginning of such movement. The spring is thus able to overcome the slightly increasing resistance which the diaphragm and connected parts oppose as the diaphragm nears the end of its movement and also preferably provides a slightly accelerated movement of the diaphragm which insures rapid return of the parts to normal position ready for a repetition of the operation.

While I have herein disclosed one desirable embodiment of the invention by way of example, I wish it to be understood that various changes in size, proportion and relative arrangement of parts as well as the substitution of equivalents may be made without departing from the spirit of the invention.

I claim:

1. Power control apparatus for a pneumatic despatch system of the vacuum minimum flow type having a transmission tube and an exhauster connected to the tube, said apparatus comprising a valve for controlling the flow of carrier impelling air current in the tube, the valve turning about an axis transverse to the tube, actuating means for initiating the opening of the valve when a carrier is inserted in the tube, and stop means for limiting opening movement of the valve, the valve completing its opening movement independently of said actuating device.

2. Power control apparatus for a pneumatic despatch system of the vacuum minimum flow type having a transmission tube and an exhauster connected to the tube, said apparatus comprising a valve for control-

ling the flow of carrier impelling air current in the tube, a pneumatic, and means actuatable by the pneumatic for initiating both opening and closing of the valve, said actuating means being so constructed and arranged as to permit the valve to complete its opening and closing movements independently of the pneumatic.

3. Power control apparatus for a pneumatic despatch system of the vacuum minimum flow type having a transmission tube and an exhauster connected to the tube, said apparatus comprising a valve for controlling the flow of carrier impelling air current in the tube, a pneumatic for actuating the valve, and a stem secured to the pneumatic, said stem having valve actuating abutments disposed at opposite sides of the valve and spaced apart to provide lost motion between them and the valve.

4. A power control apparatus for a pneumatic despatch system of the vacuum minimum flow type having a transmission tube and an exhauster connected to the tube, said apparatus comprising a valve for controlling the flow of carrier impelling air current in the tube, the valve having an aperture therethrough, a pneumatic for actuating the valve, and a stem secured to the pneumatic and extending through the aperture in the valve, said stem having an abutment element disposed at one side of the valve and being movable relative to the latter.

5. Power control apparatus for a pneumatic despatch system of the vacuum minimum flow type having a transmission tube and an exhauster connected to the tube, said apparatus comprising a valve for controlling the flow of carrier impelling air current in the tube, the valve having an aperture therethrough, a pneumatic for actuating the valve, and a stem secured to the pneumatic and extending through the aperture in the valve, the valve being mounted to turn about an axis transverse to the tube, and the aperture in the valve being at one side of its axis.

6. Power control apparatus for a pneumatic despatch system of the vacuum minimum flow type having a transmission tube and an exhauster connected to the tube, said apparatus comprising a valve for controlling the flow of carrier impelling air current in the tube, the valve being mounted to turn about an axis extending transversely of the tube, means, including a pneumatic, for swinging the valve to open position through an angle greater than the angle between the axis of the tube and the plane of the closed valve, and means for limiting the swing of the valve.

7. Power control apparatus for a pneumatic despatch system of the vacuum minimum flow type having a transmission tube and an exhauster connected to the tube, said apparatus comprising a valve for controlling

the flow of carrier impelling air current in the tube, the valve being of butterfly type and turning about an axis transverse to the axis of the tube, a pneumatic for opening and closing the valve, the valve when open being retained in such position by the air pressure, and lost motion connections between the pneumatic and valve permitting return of the pneumatic substantially to its normal position, after opening the valve, before the valve begins to close.

8. Power control apparatus for a pneumatic despatch system of the vacuum minimum flow type having a transmission tube and an exhauster connected to the tube, said apparatus comprising a valve past which the carrier impelling current travels and by which the flow of such current in the tube is controlled, the valve being of butterfly type, and means for opening the valve in response to introduction of a carrier into the tube thereby permitting such flow and for closing the valve suddenly after a predetermined interval of time thereby cutting off such flow.

9. Power control apparatus for a pneumatic despatch system of the vacuum minimum flow type having a transmission tube and an exhauster connected to the tube, said apparatus comprising a valve for controlling the flow of carrier impelling air current in the tube, a pneumatic for actuating the valve, and spring means tending to move the pneumatic in one direction, said spring means being arranged to exert an increasing force as the pneumatic approaches the end of its path of movement in such direction.

10. Power control apparatus for a pneumatic despatch system of the vacuum minimum flow type having a transmission tube and an exhauster connected to the tube, said apparatus comprising a valve for controlling the flow of carrier impelling air current in the tube, a pneumatic for actuating the valve, a spring for moving the pneumatic in one direction, and lever means interposed between the spring and pneumatic and so arranged that the spring exerts an increasing force as the pneumatic approaches the end of the path of movement in such direction.

11. Power control apparatus for a pneumatic despatch system of the vacuum minimum flow type having a transmission tube and an exhauster connected to the tube, said apparatus comprising a valve for controlling the flow of carrier impelling air current in the tube, the valve being of butterfly type and turning about an axis transverse to the tube, the valve normally being closed and, means for swinging the valve toward open position, and means for stopping the valve when it has opened to such a point that the air current in the tube tends to hold it open.

12. Power control apparatus for a pneumatic despatch system of the vacuum mini-

imum flow type having a transmission tube and an exhauster connected to the tube, said apparatus comprising a valve for controlling the flow of carrier impelling air current in 5 the tube, the valve being of butterfly type and turning about an axis transverse to the tube, the valve normally being held in closed position by air pressure, means for moving the valve to an open position such that if unrestrained the valve would continue to move in 10 the same direction under the action of air pressure, and means for preventing such continued movement.

13. Power control apparatus of the minimum flow type comprising a casing having a 15 passage adapted to connect the transmission and suction tubes of a pneumatic despatch system, a valve in said passage, a housing at one side of the casing and a pneumatic in the 20 housing, the pneumatic comprising a part which moves in a path making an acute angle with the axis of the passage in the casing, and reciprocatory means for transmitting movement of the part to the valve for opening and 25 closing the same, which means moves in the path of said part and makes substantially equal angles with the valve whether open or closed whereby equal movements of the valve are secured in both directions of travel of the 30 means.

14. Power control apparatus of the minimum flow type comprising a casing having a 35 passage adapted to connect the transmission and suction tubes of a pneumatic despatch system, a valve in said passage, a diaphragm housing at one side of the casing, a diaphragm in the housing, the housing being so arranged with respect to the casing that the plane of the 40 diaphragm is at an acute angle to the axis of the passage in the casing, and reciprocatory means for transmitting movement from the diaphragm to the valve for opening and closing the same, which means moves in the path of said part and makes substantially 45 equal angles with the valve whether open or closed whereby equal movements of the valve are secured in both directions of travel of the means.

15. Power control apparatus of the minimum flow type comprising a casing having a 50 passage adapted to connect the transmission and suction tubes of a pneumatic despatch system, said valve being normally closed and inclined with respect to the axis of the passage, a diaphragm housing at one side of the casing, a diaphragm within the housing, and a stem carried by the diaphragm and extending through an opening in the valve, the diaphragm housing being so disposed that the 55 plane of the diaphragm makes an acute angle with the axis of the passage.

16. Power control apparatus of the minimum flow type comprising a casing having a 60 passage adapted to connect the transmission and suction tubes of a pneumatic despatch

system, a pivoted valve in the casing, a pneumatic, a stem projecting from the pneumatic, and means on the stem for opening or closing the valve, the stem making substantially equal angles with the valve when the latter is closed and open respectively and thereby securing equal movement of the valve in both directions of travel of the stem. 70

17. Power control apparatus of the minimum flow type comprising a casing having a 75 passage adapted to connect the transmission and suction tubes of a pneumatic despatch system, a controlling valve in the casing, a pneumatic comprising a diaphragm within a housing, a spring for moving the diaphragm in one direction, means for adjusting the spring, means transmitting movements from the diaphragm to the valve, the diaphragm housing having a leak passage, means for adjusting said passage, the casing having a 80 minimum flow passage, and means for adjusting the latter passage, all of said adjusting means being accessible from one side of the control apparatus. 85

18. Power control apparatus for a pneumatic despatch system of the vacuum minimum flow type having a transmission tube and an exhauster connected to the tube, said apparatus comprising a valve for controlling the flow of carrier impelling air current 90 through the tube, a minimum flow of air through the tube being permitted when the controlling valve is closed, a pneumatic normally exposed on one side to the pressure in the transmission tube, means for transmitting movement from the pneumatic to the controlling valve, and means operative a predetermined time after opening of the controlling valve completely to shut off the pneumatic from the pressure in the tube and to 95 keep it shut off from the tube pressure for a predetermined time after the controlling valve closes. 100

19. Power control apparatus for a pneumatic despatch system of the vacuum minimum flow type having a transmission tube, and an exhauster connected to the tube, said apparatus comprising a valve for controlling the flow of carrier impelling air current 110 through the tube, a minimum flow of air through the tube being permitted when the controlling valve is closed, a pneumatic normally exposed on one side to the pressure in the transmission tube, means for transmitting movement from the pneumatic to the controlling valve, the pneumatic responding to pressure change in the tube resulting from introduction of a carrier and by such response opening the controlling valve, an auxiliary valve which closes a predetermined time after 115 the controlling valve opens and which opens a predetermined time after the controlling valve closes, said auxiliary valve when closed cutting off the pneumatic from pressure variations in the tube, and means for adjustably 120

determining the lag between the movements of the controlling and auxiliary valves.

20. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic normally exposed on one side to the pressure in the transmission tube, means actuatable by the pneumatic for initiating opening and closing of the controlling valve, the pneumatic responding to pressure change in the tube resulting from introduction of a carrier into the tube and by such response initiating the opening of the controlling valve, the completion of the opening of the valve resulting from differential air pressure on its opposite sides, an auxiliary valve for cutting off communication between the tube and the pneumatic, motor means including an auxiliary pneumatic for closing and opening said auxiliary valve, and an adjustable timing controller for said motor means whereby the latter is adapted to close the auxiliary valve after the controlling valve opens and to open the auxiliary valve a predetermined time after the controlling valve closes.

21. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic normally exposed on one side to the pressure in the transmission tube, means for transmitting movement from the pneumatic to the controlling valve, the pneumatic responding to pressure change in the tube resulting from introduction of a carrier into the tube and by such response opening the controlling valve, an auxiliary valve for cutting off communication between the tube and the pneumatic, an auxiliary pneumatic, a stem secured to the auxiliary valve and extending through an opening in the pneumatic, said stem having an abutment element engageable by the pneumatic for moving the stem in one direction, and means for moving the pneumatic in the opposite direction away from said abutment.

22. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic nor-

mally exposed on one side of the pressure in the transmission tube, means for transmitting movement from the pneumatic to the controlling valve, the pneumatic responding to pressure change in the tube resulting from introduction of a carrier into the tube and by such response opening the controlling valve, an auxiliary valve for cutting off communication between the tube and the pneumatic, and motor means, including an auxiliary pneumatic, for closing and opening the auxiliary valve, said motor means comprising lost motion connections between the auxiliary valve and the pneumatic permitting limited movement of the pneumatic in one direction at least without corresponding movement of the valve.

23. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic normally exposed on one side to the pressure in the transmission tube, means for transmitting movement from the pneumatic to the controlling valve, the pneumatic responding to pressure change in the tube resulting from introduction of a carrier into the tube and by such response opening the controlling valve, an auxiliary valve for cutting off communication between the tube and the pneumatic, an auxiliary pneumatic, a stem secured to the auxiliary valve and extending through an opening in the pneumatic, said stem having an abutment element engageable by the pneumatic for moving the stem in one direction, and means for moving the pneumatic in the opposite direction away from said abutment.

24. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic normally exposed on one side to the pressure in the transmission tube, means for transmitting movement from the pneumatic to the controlling valve, an auxiliary valve for shutting off the main pneumatic from the pressure in the tube, an auxiliary pneumatic for actuating the auxiliary valve, a pilot valve for the auxiliary pneumatic, said pilot valve normally being exposed on one side to atmospheric pressure and on its other to sub-atmospheric pressure, means actuatable by the main pneumatic for unseating the pilot valve

against atmospheric pressure, and means for moving the unseated valve away from its seat.

25. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic normally exposed on one side to the pressure in the transmission tube, means for transmitting movement from the pneumatic to the controlling valve, an auxiliary valve for shutting off the main pneumatic from the pressure in the tube, an auxiliary pneumatic for actuating the auxiliary valve, a pilot valve for the auxiliary pneumatic, said pilot valve normally being exposed on one side to atmospheric pressure and on its other to sub-atmospheric pressure, a rod carried by the main pneumatic, said rod extending through an opening in the pilot valve, spaced abutments disposed respectively at opposite sides of the pilot valve, one of said abutments acting to unseat the pilot valve, and a spring urging the pilot valve toward the other abutment.

26. Power control apparatus for a pneumatic despatch system of the vacuum minimum flow type having a transmission tube, and an exhauster connected to the tube, said apparatus comprising a swinging valve of butterfly type for controlling the flow of carrier impelling air current through the tube, a minimum flow of air through the tube being permitted when the controlling valve is closed, a pneumatic normally exposed on one side to the pressure in the transmission tube, lost motion connections for transmitting movement from the pneumatic to the controlling valve, an auxiliary valve for shutting off the main pneumatic from the pressure in the tube, an auxiliary pneumatic for actuating the auxiliary valve, a pilot valve for the auxiliary pneumatic, said pilot valve normally being exposed on one side to atmospheric pressure and on its other to sub-atmospheric pressure, a stem carried by the main pneumatic, said stem extending loosely through an opening in the pilot valve, an abutment on said stem, said abutment being normally spaced from the pilot valve but engageable with said valve to unseat it, and a second abutment on said stem, spaced from the first, and engageable with said pilot valve to restore it to its seat.

27. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air

through the tube being permitted when the controlling valve is closed, a pneumatic normally exposed on one side to the pressure in the transmission tube, means for transmitting movement from the pneumatic to the controlling valve, an auxiliary valve for shutting off the main pneumatic from the pressure in the tube, an auxiliary pneumatic for actuating the auxiliary valve, a pilot valve for the auxiliary pneumatic, said pilot valve normally being exposed on one side to atmospheric pressure and on its other to sub-atmospheric pressure, the main pneumatic being a stem which passes loosely through holes in the controlling valve and pilot valve respectively, and abutments on said stem for actuating the controlling and pilot valve respectively.

28. Power control apparatus for a pneumatic despatch system of the vacuum minimum flow type having a transmission tube, and an exhauster connected to the tube, said apparatus comprising a valve for controlling the flow of carrier impelling air current through the tube, a minimum flow of air through the tube being permitted when the controlling valve is closed, a pneumatic normally exposed on one side to the pressure in the transmission tube, means for transmitting movement from the pneumatic to the controlling valve, an auxiliary valve for shutting off the main pneumatic from the pressure in the tube, an auxiliary pneumatic for actuating the auxiliary valve, a pilot valve for the auxiliary pneumatic, said pilot valve normally being exposed on one side to atmospheric pressure and on its other to sub-atmospheric pressure, the main pneumatic having a stem which extends through openings in the controlling and pilot valves respectively, and an abutment on the stem at each side of the controlling and pilot valves respectively, the abutments of each pair being arranged to initiate the opening and closing of the respective valves.

29. Power control apparatus for a pneumatic despatch system of the vacuum minimum flow type having a transmission tube, and an exhauster connected to the tube, said apparatus comprising a pivoted valve for controlling the flow of carrier impelling air current through the tube, a minimum flow of air through the tube being permitted when the controlling valve is closed, a pneumatic normally exposed on one side to the pressure in the transmission tube, means for transmitting movement from the pneumatic to the controlling valve, an auxiliary valve for shutting off the main pneumatic from the pressure in the tube, an auxiliary pneumatic for actuating the auxiliary valve, a pilot valve for the auxiliary pneumatic, said pilot valve normally being exposed on one side to atmospheric pressure and on its other to sub- 115 120 125 130

atmospheric pressure, a stem carried by the main pneumatic, said stem extending through openings in the controlling and pilot valves, and an abutment on said stem engageable with the pilot valve for unseating the latter.

5 Signed by me at Syracuse, New York this 24th day of October 1928.

JAMES T. COWLEY.
